DESIGN FOR A HAND TRUCK FOR GOLF CLUBS

Arnold H. Jessen, West Hollywood, Calif.

Application March 29, 1944, Serial No. 113,060

Term of patent 14 years

(Cl. D14—3)

To all whom it may concern:

Be it known that I, Arnold H. Jessen, a citizen of the United States and a resident of the city of West Hollywood, in the county of Los Angeles and State of California, have invented a new, original, and ornamental Design for a Hand Truck for Golf Clubs, of which the following is a specification, reference being had to the accompanying drawing, forming part thereof.

In the drawing:

I claim:

The ornamental design for a hand truck for golf clubs, substantially as shown.

ARNOLD H. JESSEN.
